(57) **CLAIM**

The ornamental design for an electrical connector, as shown and described.

DESCRIPTION

FIG. 1 is a left-side perspective view of the electrical connector.

FIG. 2 is a right-side perspective view of the electrical connector.

FIG. 3 is top plan view of the electrical connector.

FIG. 4 is a left-side elevation view of the electrical connector.

FIG. 5 is bottom plan view of the electrical connector.

FIG. 6 is a front end view of the electrical connector; and, FIG. 7 is a rear end view of the electrical connector.

The broken lines in the figure drawings are included for the purpose of illustrating environment and forms no part of the claimed design.

1 Claim, 3 Drawing Sheets
